SHOWCASE

Walter A. Lapham, Chicago, Ill., assignor to E. J.
Brach & Sons, Chicago, Ill., a corporation of Illinois

Application September 1, 1948, Serial No. 148,409

Term of patent 14 years

(Cl. D80—11)

To all whom it may concern:

Be it known that I, Walter A. Lapham, a citizen of the United States, residing at Chicago, in the county of Cook and State of Illinois, have invented a new, original, and ornamental Design for a Showcase, of which the following is a specification, reference being had to the accompanying drawing, forming a part thereof.

In the drawing:

Fig. 1 is a front elevational view of a showcase, embodying my new design;

Fig. 2 is an end elevational view thereof; and

Fig. 3 is a front perspective view of the showcase.

I claim:

The ornamental design for a showcase, substantially as shown.

WALTER A. LAPHAM.
